ATTORNEY

UNITED STATES PATENT OFFICE.

BERTRAM SIMON, OF NEW YORK, N. Y.

DESIGN FOR A BADGE, BUTTON, OR SIMILAR ARTICLE OF MANUFACTURE.

53,256.

Specification for Design.

Patented Apr. 29, 1919.

Application filed February 12, 1919. Serial No. 276,666. Term of patent 3½ years.

To all whom it may concern:

Be it known that I, BERTRAM SIMON, a citizen of the United States, and a resident of the borough of Manhattan, in the city, county, and State of New York, have invented a new, original, and ornamental Design for a Badge, Button, or Similar Article of Manufacture, of which the following is a specification, reference being had to the accompanying drawings, forming part thereof.

The figure is a plan view of a badge, showing my new design.

I claim:

The ornamental design for a badge, button, or similar article of manufacture as shown.

BERTRAM SIMON.
